LOREN P. MICHAEL, OF ELMHURST, ILLINOIS, ASSIGNOR TO THE SUPERHEATER COMPANY, OF NEW YORK, N. Y., A CORPORATION OF DELAWARE

STEAM SEPARATOR

Application filed October 18, 1929. Serial No. 400,592.

This invention relates to steam separators and has for its purpose an improved arrangement for getting rid of the water separated out from the steam.

5 The invention is illustrated in the accompanying drawings in which Fig. 1 is a vertical longitudinal section of the rear portion of a locomotive equipped with a steam separator and with my improved means for disposing of the water separated out; Fig. 2 is a rear elevation of the same locomotive, portions of the cab being omitted for the sake of clearness; Fig. 3 is a view partly in section of the separator on an enlarged scale; 15 and Fig. 4 is a top view of the separator partly in section on line 4—4 of Fig. 4.

The steam delivered to the dry pipe of the modern locomotive is in a great many instances charged with a large amount of moisture. Some form of separator to separate out such moisture and deliver to the superheater or engine dry steam is, therefore, highly desirable. Such a separator would logically be located in the steam dome at the entrance to the dry pipe. One of the difficulties connected with the use of the separator in such a position is that of getting rid of the water which the separator has taken out of the steam passed through it. Means for 20 this purpose have been suggested in the past. However, the present invention provides what I regard as an improved and very effective way of disposing of this water. My improvement is applicable to cases where some auxiliary steam-using device is employed which can operate with relatively very wet steam.

40 Referring to the drawings, the rear portion of the locomotive boiler appears at 1, 2 being the steam dome and 3 the dry pipe. The steam separator is shown at 4. This separator may be of any preferred form, the one I have used for illustrative purposes being shown in a little greater detail in Figs. 3 and 4. The casing 5 has its upper part flanged over as at 7. A sleeve member 8 extends up into the casing, its top being open and its lower end communicating with the dry pipe 3 through elbow 9. Above the 45 open end of the sleeve 8 there is a conical

baffle 10. Curved blades 11 between which steam must pass on its way from the entrance 6 into the casing give the steam a whirling motion. The lower part of the casing has a slight annular enlargement 12. From this space 12 there extends tangentially outward at one point the water discharge opening 13 to which is connected the pipe 14.

55 The action of this separator will be obvious. The whirling motion of the steam causes the water particles to impinge against the wall of the casing 5 and the dry steam leaves through the central opening 8 and goes to the dry pipe while the water leaves through the connection 13. This form of separator is 35 old and forms no part of my invention except as it enters into the combination forming my invention.

This separator is shown applied to a locomotive equipped with a mechanical stoker. 70 The casing containing the screw of this stoker is shown at 15, the coal being delivered by the screw to the point 16. This stoker in no way forms part of my invention and it is, therefore, unnecessary to go into any 75 detailed description of it. The coal is distributed in this type of stoker from the point 16 to the various parts of the grate by means of the distributor jet 17. Steam is supplied to the steam jet 17 from a distributor head 80 18 through the several pipes 19—19. All of this is in accordance with the usual arrangement.

Ordinarily steam to the distributor head 18 is supplied from the steam turret in the 35 cab. According to my invention the connection from the steam turret is replaced by one from the water outlet of the steam separator. The pipe 14 in other words leads from the water outlet of the steam separator 90 to the distributor head 18. A valve 20 is placed in this pipe.

The fact that this distributor head can use relatively very wet steam without the use of such wet steam entailing any objectionable consequences, makes it possible to discharge the water from the separator into this jet. The pipe 14 passes to the jet not only the water separated out in the separator but in addition all of the steam that is required 95

to operate the jet. If desired, of course, only a portion of such steam need be supplied through 14 and an additional steam supplying connection from some other source can be connected to 18, although I have not found this necessary.

The action of the device needs no further description as it will be perfectly clear from what has been stated above. As the jets 10 discharge to atmosphere the water is very effectively removed from the steam separator. In the operation of such a locomotive the stoker and one or more of the jets are operating practically all the time and certainly 15 at all times when the separator is working, i. e. when the main throttle is open.

In practice it will be possible to make some variations in this arrangement without departing from the spirit of the invention. It 20 will be understood that the steam jet herein described as being the point to which the water is carried from the separator is only illustrative and is meant to be representative of devices for converting heat energy of steam 25 into mechanical energy and which can use steam with relatively large amounts of moisture. According to my present information it forms the best apparatus of this type to which to carry such moisture.

30 I claim:

1. In apparatus of the class described the combination of a boiler having a steam space and a water space, a pipe to conduct steam from the steam space, a steam separator 35 through which the steam flows and in which water is separated out from the steam, a steam operated device transforming heat energy of steam into mechanical energy and capable of using relatively very wet steam, and means 40 to conduct said water from the separator mingled with steam to said device.

2. In apparatus of the class described the combination of a boiler having a steam space and a water space, a pipe to conduct steam 45 from the steam space, a steam separator through which the steam flows and in which water is separated out from the steam, a steam operated device transforming heat energy of steam into mechanical energy and capable of 50 using relatively very wet steam, and a steam conduit for supplying steam to said device, said conduit leading from the water discharge opening of the separator to the steam inlet to the device for passing the separated water 55 to the device mingled with the steam operating the latter.

3. In apparatus of the class described the combination of a boiler having a steam space and a water space, a steam operated device 60 transforming heat energy of steam into mechanical energy and capable of using relatively very wet steam, a steam separator in the steam space, a steam pipe to carry the dry steam away from the separator, and a pipe to 65 carry to the steam consuming device the water

separated out in the separator together with the steam to operate the device.

4. In apparatus of the class described, the combination of a locomotive boiler, a steam separator in the steam dome, a dry-pipe to carry steam away from the separator, a coal distributing steam jet, and a conduit connecting the water discharge opening of the separator to the jet to carry away the water together with the steam required by the jet. 75

5. In apparatus of the class described the combination of a boiler having a steam space and a water space, a pipe to conduct steam from the steam space, a steam separator through which the steam flows and in which 80 water is separated out from the steam, a steam operated device in which the steam is used expansively and which is capable of using relatively very wet steam, and means to conduct said water from the separator mingled 85 with steam to said device.

6. In apparatus of the class described the combination of a boiler having a steam space and a water space, a pipe to conduct steam from the steam space, a steam separator through which the steam flows and in which 90 water is separated out from the steam, a steam operated device in which the steam is allowed to expand to atmospheric pressure and which is capable of using relatively very wet steam, and means to conduct said water from the separator mingled with steam to said device. 95
